UNITED STATES PATENT OFFICE

162,878

TRUCK MIXER

Evan S. Prichard, La Canada, Calif., assignor to Cook Bros. Equipment Co., Los Angeles, Calif.,
a corporation of California

Application May 1, 1950, Serial No. 9,620

Term of patent 14 years

(Cl. D14—3)

To all whom it may concern:

Be it known that I, Evan S. Prichard, a citizen of the United States, residing at La Canada, in the county of Los Angeles and State of California, have invented a new, original, and ornamental Design for Truck Mixer, of which the following is a specification, reference being had to the accompanying drawing, forming a part thereof, and in which:

Fig. 1 is a side elevational view of the truck mixer showing my new design.

Fig. 2 is a plan view of the truck mixer.

Fig. 3 is a view similar to Fig. 1 taken from the opposite side of the truck mixer.

Fig. 4 is a front end elevational view.

I claim:

The ornamental design for a truck mixer, as shown.

EVAN S. PRICHARD.
